UNITED STATES PATENT OFFICE.

FRANK A. KLAINE, OF NEWPORT, KENTUCKY.

DESIGN FOR A COOKING-STOVE.

SPECIFICATION forming part of Design No. 28,219, dated January 25, 1898.

Application filed November 23, 1897. Serial No. 659,639. Term of patent 3½ years.

To all whom it may concern:

Be it known that I, FRANK A. KLAINE, a citizen of the United States, and a resident of Newport, in the county of Campbell, State of Kentucky, have invented a certain new and original Design for a Cook Stove or Range, of which the following is a specification.

My design for a cook stove or range is illustrated in the accompanying drawing, which is a perspective view.

As shown, the leading features of my design are the form of the stove, the ornamental base therefor, the ornamentation on the oven-door, the ornamentation on the ash-pit door, and the ornamentation on the support for the mantel-shelf.

The stove is quadrangular in form, the front and sides of its body being divided into two sections by an outwardly-projecting bead A, and each of the sections thus formed being divided into a series of panels by means of ornamental vertical corner-pieces B B'. The corner pieces or strips B B' on the upper section extend from the aforesaid division-bead A to the under side of the top C of the stove, and the strips B' extend from said bead A downward to a base flange or rim D, which rests on the floor or support for the stove and is ornamented in the manner illustrated.

A door E is arranged in the front panel of the lower section of the stove, the space between each end of said door and the adjacent corner-pieces B' being more or less filled up by an ornamental scroll F.

In the front panel of the upper section of the stove are arranged the main oven-door G, the door H, communicating with the firebox, and the ash-pit door K. The main door is shown as a drop-door, ornamental hinges g being arranged at the lower corners thereof, and a handle or pull g' being arranged centrally of the upper edge.

An inscription-plate L of the form shown

is arranged centrally of the door G, it being arranged within a space which is bounded at 45 its sides or ends by scrolls M. The space between the upper ends of each of said scrolls M and the handle g' is traversed by a relatively narrow band N, while the lower ends of such scrolls are connected by an ornate band N', and the spaces between the lower corners of the door G and the aforesaid scrolls M are partially filled by leaf-like forms O.

The ash-pit door K is ornamented by four 55 flower-like forms P, each springing from a quatrefoil center-piece p and separated one from the others by a series of elliptical-shaped projections p'.

The support for the mantel-shelf is bounded 60 at its vertical edges by corner-pieces Q, and the front is divided into two spaces R R' by means of three ornamental scrolls or sets of scrolls S of the form shown. In the space R is arranged an inscription-plate, while in the 65 space R' is situated a fan-shaped draft-regulator T.

What I claim is—

1. The design for a cooking stove or range, substantially as herein shown and described. 70
2. The design for the oven-door of a cooking stove or range, substantially as herein shown and described.

3. The design for the ash-pit door of a cooking stove or range, substantially as herein shown and described. 75

4. The design for the mantel-shelf support of a cooking stove or range, substantially as herein shown and described.

In testimony whereof I have hereunto subscribed my name in the presence of two witnesses.

FRANK A. KLAINE.
